UNITED STATES PATENT OFFICE.

LECTICIO SALCINES, OF GUANTÁNAMO, CUBA.

CENTRIFUGAL MACHINE.

1,253,428.

Specification of Letters Patent. Patented Jan. 15, 1918.

Application filed January 3, 1916. Serial No. 69,837.

To all whom it may concern:

Be it known that I, LECTICIO SALCINES, a citizen of the Republic of Cuba, residing at Guantánamo, Province of Oriente, Cuba, have invented new and useful Improvements in Centrifugal Machines, of which the following is a specification.

This invention relates to that class of centrifugal machines which work continually and in which material to be treated is passed between an outer basket and an inner drum suitably spaced from the basket, said basket and said drum each having rotary motion at different rates of speed, one with respect to the other, to regulate the passage through the machine of the material to be dried. One object of the invention is to obtain a continuous regulation of the filtering action in said class of machines.

20 A further object of the invention is to obtain a perfect and constant cleaning of the basket or filtering drum, on the inner side thereof.

25 My invention consists in certain novel features in the construction of centrifugal machines and in a novel arrangement of parts such as are hereinafter described and claimed.

30 Referring to the accompanying drawings, which form a part of this application, and in which similar letters refer to similar parts throughout the several views:—

35 Figure 1 is a vertical sectional view of a centrifugal machine provided with the improvements forming the subject matter of this invention.

40 Fig. 2 is an enlarged vertical sectional view of the inner drum and the device adapted to admit steam and compressed air into the basket.

45 Fig. 3 is a transverse cross-section through the helical rim on the outer side of the inner drum, to distribute a fluid into the basket and in which are mounted scrapers adapted to reciprocate under the action of compressed air.

Fig. 4 is a similar view to that of Fig. 3, showing a modified position of scraper.

50 Fig. 5 is a transverse cross-section of said rim showing the distribution of the fluid on the inner side of the basket.

Fig. 6 is a section taken on line *a* *b* of Fig. 4.

Fig. 7 is a perspective view of the basket or filtering drum showing the position of a register door provided therein.

Fig. 8 is a perspective view of the outer casing of the machine, provided with a register door.

Fig. 9 is a perspective view of a portion 60 of the helical rim on the inner drum, showing the arrangement of the moving scrapers and steam distributing means.

Fig. 10 is a detailed vertical sectional view of the mechanism regulating the entry of 65 the material to be treated.

Fig. 11 is a transverse horizontal section on line 9—11 of Fig. 10.

Fig. 12 is a detail showing a top plan view of the cylindrical body for feeding the material to be treated into the basket.

Referring to the annexed drawings, 19 and 20 are standards or columns forming part of a frame supporting a ring-shaped platform 40 on which is rigidly mounted a 75 cylindrical casing C open at the central part of its bottom. A vertical shaft O which is revolubly supported upon the foundation E passes upward through the casing C. On the shaft O there is rigidly fixed a cylinder 80 A which on its outer surface is provided with a helix-shaped rim 4, and concentrically with said cylinder A and involving the same there is mounted a perforated cylinder or filter B which is provided on its 85 interior face with a filtrating metallic web suitably disposed thereon. The filter B is fixed at the bottom to a sleeve Q surrounding the shaft O which is supported by its lower edge upon the balls of a ball-bearing 90 D fixed on the shaft O; and upon the same sleeve Q there is formed a pulley H whereby movement is transmitted to the filter B from a suitable power supply. The shaft O carries beneath the ball-bearing D, three 95 pulleys, *p*, *p'*, *p''* by means of which different speeds may be obtained from any power supply or engine. Filter B is provided at the top with an opening and a suitable ball-bearing around a vertical flange *b* 100 projecting downward from the upper part of casing C, and on the upper opening of casing C formed by the flange *b*, there is a cylindrical body *p* wherein runs the mixture or material that is to be filtered. This cylindrical part *p* is provided with a cover formed of two halves 42 and 43 joined together by a hinge 44, the halves of which either open or close on the vertical fluid inlet tube 23 in the cylinder A, which tube 23 extends 110 vertically upward from the center of the drum A. The cover 42—43 opens to give

admission to the mixture or material that is to be treated into the cylinder P. On the upper portion of the frame 19, 20 there is mounted over the cylinder P a trough S for supplying the material that is to be treated, the supply being regulated through the trough by means of a valve N which closes from beneath on the outer edge of the central lower opening of said trough, the stem 10 of said valve N being articulated with the end of a lever L fulcrumed upon the upper edge of the trough S which connects on its other end with an electric regulating mechanism for the control of the discharge of 15 the mixture or material from the trough S to the cylinder P, the construction of which is as follows: On the upper top of casing C and communicating with the inside of the cylinder P there are disposed a series of 20 horizontal cylinders c, arranged in groups of two to two opposed, there being four shown in Fig. 11. Each of these cylinders is provided with a piston 5 or 6, the stem of which passes through a stationary central vertical partition 48. Piston 5 or 6 normally remains situated in a position next to the opening communicating with the cylinder P, by virtue of elastic tension produced by a spiral spring 7 or 8 located 25 between the piston and the transverse partition 48, the stem of the piston 5 or 6 having a point 9 or 11, of a material adapted to conduct electricity, and in front of this point there is located inside of each cylinder c an 30 electric contact 10 or 12, which is connected by means of conducting wire 49 with the binding post 50 of a box 51 mounted on the top 19' of the frame supporting the apparatus, said box 51 containing an electro- 35 magnet 13 and a generating battery 14. The coil of the electro-magnet is connected at one end to the binding post 50 and at the other end with the negative pole of the battery, and the positive pole of the battery 40 is connected with another binding-post 52 from which a wire 53 leads to the binding post 54 provided on the periphery of the cylinder P. As shown in Fig. 11, the contact-points 10, 12 of the horizontal cylinders are 45 preferably in connection with each other by means of a wire 18 mounted on insulated supports 58' circularly disposed around the cylinder P and with which the wire 49 connects in a single point 48, completing the 50 circuit with the electro-magnet and the battery. The electric circuit will be closed when the points 9, 11 touch the contacts 10, 12 through connections as follows: 10, 49, 50, 13, 14, 52, 53, 54, P, c, 6, and 9. The 55 mechanism operated by the electro-magnet 13 consists of a stem 15 articulated with the end of the lever L and which is attracted to the inside of the electro-magnet 13 when the current of the battery 14 passes through 60 the coil of the magnet.

The outer helix-shaped rim 4 of the rotary cylinder A serves for conducting the solid matter separated from the liquid matter by centrifugal force to the bottom of the filter B, from where it falls through the 70 openings 38 into curved conductors 39 fixed at the bottom of the casing C and provided with a lower opening which may be opened or closed by means of sliding gates 45, 46 for the purpose hereinafter stated. Said 75 helical rim is at intervals provided all along its length with scrapers 3 to prevent the formation of a cake of excessive thickness on the metallic web of the filter B, said scrapers 3 being actuated by compressed 80 air. The scrapers 3 are vertically positioned and are mounted by means of a stem 33 with which they are provided on a framework 34 mounted on the end of the stem 35 of a piston 37 adapted to reciprocate inside of a 85 cylindrical gap 56 formed transversely in the helical rim 4 and in the wall of the cylinder A, said piston stem being guided through a hole in a transversal partition 57 of said gap. Interposed between that 90 partition and the piston 37 is a spiral spring 36, and the piston 37 is provided with a stop 58. Behind the piston 37, there is a compressed air chamber 32 to which the air is admitted by a tube 32' inside of the helical rim 4 adapted to feed all the chambers 95 32. In normal position the scraper 3 introduced into the cylindrical gap 56, but when there is compressed air in the chamber 32 acting on the piston 37, the scraper 3 is forced outward until it comes to a small distance from the metallic web of the filter B, the spring 36 and the stop 58 being regulated in such a way that under the action of the compressed 100 air on the piston 37, the scraper 4 will come to a distance of about $\frac{1}{2}$ of an inch from the metallic web of the filter B. In the inside of the rim 4 there are also disposed near its upper and lower faces tubes 30 and 31 that 105 follow the circumvolutions of the rim and serve to conduct steam to be distributed on the metallic web of the filter B to conduits 2 of reduced section through which the steam is allowed to escape against the filter B. 110 These outlets 2 are spaced upon the rim in alternation with the scrapers (Fig. 9). There are disposed on places near these steam-outlet tubes 2 and on the outer periphery of the rim 4, fixed brushes 47 which 115 assist the action of the scrapers 4. The steam is conducted to the tubes 30 and 31 by a wide vertical conduit 28 that occupies the axial line of the cylinder A and is fixed to the same and from said conduit horizontal 120 radial tubes 59 and 60 lead to the helical tubes 30 and 31. The conduit 28 extends at its upper end inside of a closed fixed box 27 in respect to which said conduit has a 125 rotary movement by means of a ball-bear- 130

ing 28. Steam is admitted to the box 27 from any steam generator (not shown) by a feeding pipe 61 wherein a regulator R of any desired construction is interposed, and which provides an intermittent feed of steam to the box 27. Rigidly fixed on this box is another box 26 having an outlet at the bottom into a vertical pipe 24 which leads downward and is concentrically disposed on the inside of the vertical conduit 23 and extends lower than the same, communicating with the helical tube 32' in a circumvolution of the rim 4 lower than that whereby the steam is fed to the helical tubes 30 and 31 by the radial tubes 59 and 60. The vertical tube 24 rotates inside of the box 26 by means of a ball-bearing 29 and into the box 26 the compressed air is fed from any kind of compressor (not shown) by the feed pipe 62, in which there is interposed a regulator R' of any desirable construction which provides an intermittent feeding of compressed air inside of the box 26.

25 Filter B is provided with a lateral register door 22 and opposite to this door in the casing C is another lateral register door 21 by which means the inside of filter B may be reached for the cleaning of same if it should be required. Casing C presents in its lower part an annular channel 63 for the gathering of the liquid part once separated from the solid through the perforated wall and filtrating web of the filter B, said channel being provided with a suitable drain (not shown).

Instead of steam, tubes 30 and 31 may carry water or other fluid to conduits 2 for cleaning the filtrating web of the filter B.

40 The operation of the apparatus is as follows:—The cylinder A and the filter B are rotated at different rates of speed by means of the shaft O and the sleeve Q, from any source of power, and the cover of the cylinder P is opened around the hinge 44, to separate its halves 42, 43 and then entry of the mixture to be filtered into the cylinder P is allowed by opening valve N by hand action of the lever L, and the mixture that flows into the cylinder P will fall direct upon cylinder A and by virtue of the action of centrifugal force, it will be thrown against the wall of filter B. It is then caught by the helical rim 4 of the inner cylinder A, being compelled to move downward by said helical rim due to the difference of speed rates of the cylindrical bodies A and B; and while the mixture travels on the helical rim 4 it will lose all its liquid part which will flow across the filtrating web and through the perforations of the filter B and fall into the space comprised between filter B and the casing C, said liquid part being received by the channel 23 of the latter, while the solid part which does not pass

through the filter falls through the openings 38 into the discharging conduits 39, from which it passes through the gates 45, 46 when they are opened and is received by suitable receptacles. While cylinder P is full of the mixture to be filtered, said mixture while flowing downward presses against the pistons 5, 6 of the horizontal cylinders c, against the elastic action of the springs 7, 8, thus making the points 9, 11 75 touch the contacts 10, 12, so that the circuit 10, 49, 50, 13, 14, 52, 53, 54, P, c, 6 and 9 is maintained closed and the current that goes through the coil of electro-magnet 13 keeps the moving stem 15 drawn inside the coil 80 which stem in turn maintains by means of the lever L, the valve N closed against the lower edge of the trough S containing the mixture to be filtered. But when cylinder P is emptied of the mixture to be filtered, 85 there being no pressure exerted to counteract the spring pressure on the pistons 5, 6, of the horizontal cylinders c, these retract to their normal position due to the elastic action of the springs 7, 8, and the contacts of 90 the points 9, 11 with the contacts 10, 12 are broken and the electric circuit 10, 49, 50, 13, 14, 52, 53, 54, P, c, and 9 is opened. Therefore no current whatever passes through the coil of the electro-magnet 13 and the moving 95 stem 15 is raised due to the weight of valve N on the opposite end of the lever L and the discharge of the mixture from the trough S is permitted again by the descent of said valve N, the cylinder P again being filled with 100 mixture, until by the pressure of this mixture on the pistons 5, 6, the above mentioned electric-circuit is again closed and closes the valve N. By this means the feeding of the mixture to be filtered in the apparatus is 105 automatically controlled.

During the operation on the interior face of the filter B there is formed a cake that would grow thicker until further filtration became impracticable, but as formerly explained, the regulators R' and R will furnish an alternative feeding of compressed air and steam into the tubes 32 and 30 and 31 respectively. The compressed air that intermittently arrives in the chamber 32' 110 from the tube 32, running through the box 26 and the vertical tube 24, intermittently acts on the pistons 37 making these advance inside of the gaps 56 and making the scrapers 3 project from the outer periphery 115 of the helical rim 4, remaining at a distance of about $\frac{1}{2}$ of an inch from the filtrating web, and due to the rotary movement of the cylinder A at a different rate of speed from the filter B, the scrapers will scrape the cake 41 120 gathered on the filtrating web, reducing its thickness to about $\frac{1}{2}$ of an inch. Since the scrapers never actually touch the filtrating web, this never suffers any wear. When the cake has been reduced the steam that runs 125

out through the outlets 2 on the helical rim 4, and which is intermittently admitted by regulator R' through the box 27 and the tube 23, acts on the remaining cake which 5 has been reduced to a thickness of about $\frac{1}{8}$ of an inch and which could not be eliminated by the scrapers 3, said remaining cake thus being destroyed by steam. Therefore 10 the filtrating web is constantly kept clean on its outer face and the action of filter B will not be interrupted.

Moreover, when the compressed air action and that of the steam, as already explained, is not wholly effective, by closing the gates 15 45, 46 of all the conduits 39 discharging the solid filtered mixture, the space comprised between the cylinder A and the filter B might be flooded with steam under pressure for completing the destruction of the 20 remainder of the cake on the filtrating web and thus making a general cleaning throughout.

Though for purposes of illustration I have shown and described a suitable form for carrying out my invention, I do not wish to limit myself to the particular construction 25 of the apparatus as it has been demonstrated but it is my intention that any slight changes which could be made on the apparatus will be comprised in the broad scope of 30 my invention, which is as follows:

What I claim is:

1. In centrifugal machines in combination, a casing and a basket, a feeding chamber to the basket, and means arranged in 35 said chamber whereby the entry of the material to be filtered is controlled by the pressure of the material itself against the walls of said chamber.

2. In centrifugal machines, in combination, a casing and a basket, a chamber through which the material to be treated is fed toward the basket, a material feeding trough arranged above said chamber and 45 provided with a discharge valve, means for giving the valve of the trough a reciprocating movement, means in the walls of said chamber adapted to be moved by the pressure of the material against the walls of the 50 chamber, and means connecting the latter means with the means actuating the valve of the feeding trough, thereby controlling the discharge of the material from the feeding trough.

3. In centrifugal machines, the combination with a casing and a basket, of a cylindrical chamber through which runs the material to be treated toward the basket, a material feeding trough arranged on said 60 cylindrical chamber and provided with a discharging valve, means for giving the valve a reciprocating movement, a series of cylinders arranged around said chamber and opening into the same, pistons in said cylinders which by the action of elastic springs

normally stand on the inside of the cylindrical chamber communicating with the basket, means for closing an electric circuit in which an electro-magnet is interposed, when the pistons referred to are pushed by 70 the pressure of the material against the wall of the cylindrical chamber, and means connecting the core of the electro-magnet with the means for giving the discharging valve a reciprocal movement, thereby controlling 75 the discharge of material from the feeding gap.

4. In centrifugal machines, in combination, a casing and a perforated rotary member, an unperforated member within said 80 perforated member and rotating at a different rate of speed from that of the perforated member the unperforated member being provided on its outer periphery with a helix-shaped rim, said rim having a series of conduits with discharge openings in front of the filtrating surface on the perforated member, and means for admitting a fluid into the conduits of the helix-shaped rim 85 in an intermittent manner.

5. In centrifugal machines, in combination, a casing and a rotary perforated member, an unperforated member within said 90 perforated member rotating at a different rate of speed from that of the perforated member, this unperforated member having on its outer periphery a helix-shaped rim provided with longitudinal conduits, radial conduits communicating with said longitudinal conduits and opening at the periphery of the rim in front of the filtrating surface of the perforated member, a conduit for distributing a fluid to said longitudinal conduits of the helix-shaped rim placed axially with respect to the perforated and the unperforated members, said distributing conduit extending outside of the latter member, and means for feeding a fluid in an intermittent manner to said distributing conduits.

6. In centrifugal machines, in combination, a casing and a rotary perforated member, an unperforated member within said 100 perforated member and rotating at a different rate of speed from that of the perforated member, a series of scrapers mounted on the outer periphery of the unperforated member, said scrapers being adapted to have radial movement, means for radially moving said scrapers under the action of a compressible fluid, and means for feeding a compressed fluid in an intermittent manner to the said moving means.

7. In centrifugal machines the combination with a casing and a rotary perforated member, of an unperforated member rotating at a different rate of speed from that of the perforated one, and located inside of 115 said perforated member, a series of pistons located in substantially radial gaps of the 120

wall of the unperforated member, these gaps forming compression chambers, scrapers mounted on the ends of the stems of said pistons, and means for feeding a compressible fluid in an intermittent manner into said compression chambers and against the said pistons to make the scrapers move forward close to the filtrating surface of the perforated member, without touching it.

10 8. In centrifugal machines, the combination with a casing and a rotary perforated member, of an unperforated member rotating at a different rate of speed from that of the perforated one and located inside of said perforated member, this unperforated member having on its outer periphery a helical rim, a series of compression chambers formed in substantially radial directions across said rim, pistons within said chambers and adapted to reciprocate against the elastic action of springs, scrapers mounted on the end of said pistons, so that in normal position the scrapers are retracted within the helical rim, a conduit disposed longitudinally within the rim to supply compressible fluid to the compression chambers, a conduit for distributing the fluid to the longitudinal conduit of the rim, said distributing conduit being axially disposed with respect to the perforated and unperforated members, and extending outside of the latter, and means for feeding a compressible fluid in an intermittent manner to the mentioned distributing conduit, so that under action of compressible fluid on the pistons inside of the compression chambers these compel the scrapers to run out from the

rim to a previously determined distance from the filtering surface of the perforated member.

40

9. In centrifugal machines, the combination with a casing provided with discharging conduits for filtrated solid matter, and a basket having openings for placing the interior of the basket in communication with said conduits, of gates arranged to close off the discharge openings of said conduits to allow the cleaning of the filtrating surface of said basket when a fluid is admitted into the casing.

50

10. In centrifugal machines, in combination with a casing and a perforated rotary member, an unperforated member rotating at a different rate of speed from that of the perforated member and located inside of this, the unperforated member being provided on its outer periphery with a helix-shaped rim which presents a series of conduits with discharge openings in front of the filtrating surface of the perforated member and a series of immovable brushes projecting from said rim, each brush being interposed between two discharge openings, and means for providing a flow of a fluid into the conduits of the helix-shaped rim in an intermittent manner.

55

In testimony whereof, I have signed my name to this specification in the presence of two subscribing witnesses.

LECTICIO SALCINES.
